APPARATUS FOR MANUFACTURING LUSTER-FREE RAYON

Yukichi Asakawa, Tokyo, Japan

Application March 23, 1936, Serial No. 70,480

3 Claims. (CL. 18-8)

My invention relates to an apparatus for manufacturing rayon having no unpleasant luster heretofore inevitable in the formation of artificial silk.

5 The principal object of my invention is to manufacture rayon having no bright luster.

In the rayon art, the artificial silk is manufactured by extruding the rayon liquid through nozzles of a rayon pot. According to my invention, means are provided for changing the 10 diameter of the extruded rayon thread regularly by applying a high frequency potential to the spinning nozzle for bending or twisting the extruded rayon forming solution.

15 My invention will be better understood from the following description taken in connection with the accompanying drawing and its scope will be pointed out in the appended claims.

In the drawing, Fig. 1 is a diagrammatic vertical section of an apparatus embodying my invention, Fig. 2 is a similar view of a modification which is further associated with means for bending or twisting the extruded thread, and Figs. 3 to 5 illustrate in perspective and plan views respectively various forms of the electrode to be associated with the arrangement of Fig. 2.

Referring to Fig. 1, numeral 1 represents a container; 2 designates the rayon forming solution such as nitro-cellulose solution and 3 is a small spinning nozzle provided at the bottom of the container for extruding the solution 2. If desired, a number of nozzles 3 may be provided in the container 1. According to my invention, the nozzle 3 is made of an electric conductor and the container 1 is insulated from the former through the insulating member 5. The conductor 3 is supplied with a high frequency alternating current voltage higher than 1,000 volts and having a frequency higher than several thousand cycles. For 20 these purposes, the conductor portion 4 is connected to a high frequency source through a high frequency transformer 6. The source includes a main oscillator valve 8 and an auxiliary high frequency oscillator 7 which is connected to excite the grid of the main valve 8.

45 Thus, the rayon forming solution 2 will be subjected to a high alternating current voltage having a frequency higher than 1000 cycles when it is extruded from the nozzle 3. Thus the particles constituting the solution are charged to be repelled from each other and the kinetic viscosity of the rayon forming solution is decreased. Accordingly the extruding velocity of the solution is not only increased, but also since the particles of the extruded thread are charged with

5 electric charge of opposite polarity in succession upon extrusion, the extruding velocity is not uniform so that the surface of the thread 9 may be finely corrugated as shown in the drawing, and the unpleasant glaring luster of the thread is practically obviated.

Fig. 2 illustrates a modification of the apparatus in which one or more external electrodes are further associated with the arrangement of Fig. 1 for bending or twisting the thread. In the 10 modification, the external electrodes 10 of any desired form are arranged along the thread 9 in the zone in which the thread 9 is not yet completely solidified. The external electrodes 10 are supplied with an alternating current voltage 15 through a transformer 11 from an alternating current source 12. With this arrangement, variable torsion or bending may be given to the thread by suitably selecting the phase, the frequency or the polarity of the applied voltage from 20 sources 8 and 12. Thus, according to my process, the rayon forming solution 2 is charged with a certain polarity from the source 8 at the outlet of the pot 1 and keeps the charge after it is extruded. Accordingly, if the external electrode 25 10 has an opposite polarity, the semi-solid thread 9 will be attracted towards the electrode 10 and the thread is put under tension to accelerate the extrusion of the liquid 2 from the pot 1. Simultaneously, the thread is bent as shown in the 30 drawing with the result of obviating undesirable luster.

Any desired electrode as shown in Figs. 3 to 5 may be adopted as the external electrode 10 of Fig. 2. Fig. 3 shows an electrode 13 of a half 35 ring form which may be used for bending the thread as shown in Fig. 2.

Fig. 4 shows an electrode 14 of a ring form. With the electrode 14, the bending is not given to the thread, but the thread may be corrugated. 40

In Fig. 5, the ring electrode 15 is divided into three conducting segments by means of the insulating spacers 16 and the segments are respectively connected to the terminals of a three phase transformer 17. 45

With this arrangement, a rotating electric field is produced within the ring electrode 15 so that the particles constituting the thread are subjected to a revolving force. The thread is twisted 50 and the luster is obviated more positively.

I do not desire my invention to be limited to the embodiments shown and I intend in the appended claims to cover the modifications within the spirit and scope of my invention.

What I claim as new and desire to secure by Letters Patent of the United States, is

1. Apparatus for manufacturing luster-free rayon comprising, a spinning nozzle, means for supplying the rayon forming solution to said nozzle, a high frequency alternating current voltage source, and means for applying a high frequency alternating current voltage to said nozzle from said source.
- 10 2. Apparatus for manufacturing luster-free rayon comprising, a spinning nozzle, means for supplying the rayon forming solution to said nozzle, means for applying a high frequency alternating current voltage to said nozzle, and external electrodes arranged along the extruded solution, said electrodes being supplied with electric potentials in order to influence the charged extruded solution.

3. Apparatus for manufacturing luster-free rayon comprising, a spinning nozzle, means for supplying the rayon forming solution to said nozzle, means for applying a high frequency alternating current voltage to said nozzle, external ring electrodes arranged along the extruded solution, each of said electrodes being divided into a plurality of segments which are respectively connected to the terminals of a polyphase electrical source having a number of phases equal to the number of said segments in order to produce a rotating electrical field, whereby the charged extruded solution passing through said ring electrodes is twisted.
